UNITED STATES PATENT OFFICE.

RUDOLF WOLF, OF NEW YORK, N. Y., AND HENRY G. PIERSON, OF SOUTH ORANGE, NEW JERSEY, ASSIGNEES TO FOOTE, PIERSON & CO. (INC.), OF NEW YORK, N. Y., A CORPORATION OF NEW YORK.

LIGHTNING ARRESTER.

Application filed May 10, 1920. Serial No. 380,054.

To all whom it may concern:

Be it known that we, RUDOLF WOLF, a citizen of the present government of Germany, and a resident of New York city, Bronx County, State of New York, and HENRY G. PIERSON, a citizen of the United States, and resident of the city of South Orange, county of Essex, State of New Jersey, have invented a certain new and useful Improvement in Lightning Arresters, of which the following is a specification.

Our invention relates to lightning arresters for telegraph wires and the like.

Among the objects of the present invention it is aimed to provide an improved device for telegraph wires and the like that will serve both to arrest lightning and in addition take care of high tension currents that may be crossed in. Due to the powerful wind storms frequently accompanying electric storms, telegraph wires and the like in the vicinity of electric light and power conductors are frequently thrust into contact with such conductors to constitute what is commonly known as a cross. Should such a cross exist, and the lightning by jumping to the ground establish an arc for the power circuit, the latter might develop sufficient current to melt the cable leading from the line wires to the arresters. The present invention aims to provide an improved device that will not only arrest the lightning but in addition will take care of such high tension currents without, on that account, requiring the device thereafter to be reset, reconnected, or in any way readjusted.

The invention further contemplates certain features of construction particularly adapted to a device of this class.

These and other features, capabilities and advantages of the invention will appear from the subjoined detailed description of certain specific embodiments thereof illustrated in the accompanying drawings in which,

Figure 1 is a fragmental plan illustrating a number of the arresters grouped together.

Figure 2 is a side elevation of a single arrester of the type illustrated in Fig. 1.

Figure 3 is a plan of another type of arrester, and

Figure 4 is a fragmental portion of still another type of arrester.

In the embodiment illustrated in Figs. 1 and 2, there is shown a supporting block 5

preferably composed of porcelain or the like having two enlarged end portions 6 and 7, a medial supporting portion 8 and two intermediate diminished cylindrical portions 9 and 10, connecting the end portions 6 and 7 with the medial portion 8.

The end portions 6 and 7 are provided with recessed seats 11 in alinement with one another and disposed in a plane, a slightly greater distance removed from the alined surfaces of the cylindrical portions 9 and 10 than the supporting surface 12 of the medial supporting portion 8 is removed therefrom. The seats 11 and surface 12 receive a metal plate 13, the medial portion of which is pressed into engagement with the surface 12, so that the ends of the plate 13 which engage the seats 11 are disposed a slightly greater distance removed from the alined surfaces of the cylindrical portions 9 and 10 than the medial portion thereof engaging the surface 12 is removed therefrom.

The end portions 6 and 7 are provided with binding posts 14, 15, respectively, the binding post 14 being connected by a conductor 16 to the line, and the binding post 15 being connected by a conductor 17 to the instruments. A conductor 18 formed into coils 19 and 20 extends from the binding post 14 along a recess 21 formed in the end portion 6, around the cylindrical portion 9, through a recess formed in the medial portion 8, around the cylindrical portion 10, and then along a recess 22 formed in the end portion 7 to the binding post 15.

By means of the flexure of the plate 13 caused by being pressed into engagement with the seats 11, and the surface 12 slightly offset relative to the seats 11, it will be seen that the distance of the plate 13 from the coils 19 and 20 gradually becomes less as the medial portion 8 is approached. The plate 13 is connected to ground by means of a binding post 23. As a discharge of lightning is induced through the line 16 it will pass through the coils 19 and 20 and discharge therefrom to the plate 13 and be thereby grounded. The distance of the plate 13 from the convolutions of the coils 19 and 20, nearest the end portions 6 and 7 is about one-eighth (1/8) of an inch, while in the vicinity of the medial portion 8, the distance is about one-thirty-second (1/32) of an inch. This causes the arc of lightning discharge to

be broken up into a dozen or more little discharges, no one of which is of sufficient intensity to raise a burr on the plate 13.

The present invention contemplates combining the arrangement of lightning arrester just described with means for dissipating and arresting high tension currents that might be crossed in. For this purpose, the embodiment illustrated in Figs. 1 and 2 is provided with plates 24 and 25 which are connected to the binding posts 14 and 15 respectively, and extend therefrom toward one another for a substantial distance over plate 13. The ends 26 and 27 of these plates are slightly tapered and rounded, and bent upwardly from the plate 13 in an arcuate direction. The distance of the plates 24 and 25 from the plate 13 varies throughout the length of the plates, the distance being least, nearest the end portions 6 and 7 and increasing as the ends 26 and 27 are approached. By means of this variation a high tension current, if received either by the conductor 16 or conductor 17 will be distributed throughout the lengths of the plates 24 and 25 and not be localized whereby the formation of burrs caused by a localized discharge is guarded against. It has been found that by this arrangement, the high tension currents which cannot pass through the coils 19 and 20 and discharge therefrom through the plate 13 will pass through the plates 24 and 25 and discharge therefrom to the plate 13 to be grounded, and that whatever current is carried to the ends 26 and 27 will be dissipated therefrom into the atmosphere.

In Fig. 4 the high tension plate 28 there shown is provided with a more pronounced curve, as compared with the plate 25 of Fig. 2, and has a greater portion of its length bent upward from the plate 13. It has been found that this arrangement is particularly advantageous with the heavier high tension currents.

The modification shown in Fig. 3 combines the form of lightning arrester illustrated in Figs. 1 and 2 with a different form of high tension arrester. The high tension arrester here provided comprises essentially two end plates 30 and 31 extending toward one another from the binding posts 32 and 33, and along ground plate 34, similar to the ground plate 13 shown in Figs. 1 and 2. The ends of the plates 30 and 31 are serrated to form the saw teeth 35 and 36 which are opposed to the serrated ends 37 and 38 of a medial plate 39, secured to a medial binding post 40 which is connected to ground. The discharge of high tension current in this modification passes along the plates 30 and 31, discharging to the ground plate 34 and whatever current remains jumps from the saw teeth 35 and 36 to the saw teeth 37 and 38 of the plate 39 and is thereby grounded.

A plurality of arrester units may be ar-

ranged in a group, as illustrated in Fig. 1. In such an arrangement the ground plates 13 of the several units are connected by means of latches 41 as shown, and frequent taps 42, of wire preferably smaller than the line wire, should be made from all, or any number, of the binding posts 41 to a ground wire 43.

Having thus described the invention what is claimed as new and desired to be secured by Letters Patent, is:—

1. A device of the character described, comprising a coil adapted to be placed in the line to be protected, and a ground plate arranged longitudinally of the coil, there being a gap of varying width between the coil and plate.

2. A device of the character described, comprising a coil adapted to be placed in a line to be protected, a conductor plate adapted to be connected to the line, and a ground plate disposed between the conductor plate and the coil and out of contact with said coil and conductor plate whereby said ground plate will receive discharges from the coil and conductor plate.

3. A device of the character described, comprising a coil adapted to be placed in a line to be protected, a conductor plate adapted to be connected to the line, and a ground plate disposed between the conductor plate and the coil whereby said ground plate will receive discharges from the coil and conductor plate, there being a gap of varying width between the plates.

4. A device of the character described, comprising a coil adapted to be placed in a line to be protected, a ground plate arranged longitudinally of the coil, there being a gap of varying width between the plate and coil, and a conductor plate adapted to be connected to the line, there being a gap of varying width between the plates, said ground plate being disposed between the conductor plate and the coil.

5. A device of the character described, comprising a coil adapted to be placed in a line to be protected, a ground plate arranged longitudinally of the coil, there being a gap of varying width between the plate and coil, and a conductor plate adapted to be connected to the line, there being a gap of varying width between the plates, said ground plate being disposed between the conductor plate and the coil, said conductor plate having one end thereof curved in an arcuate direction away from the ground plate.

6. A device of the character described, comprising a coil adapted to be placed in a line to be protected, a ground plate extending longitudinally of the coil for its entire length and being separated from the coil by a gap, said gap increasing in width from the medial line of the ground plate in both

directions toward the ends thereof, a conductor plate mounted near each end of the ground plate and extending toward the medial line thereof, means for connecting the 5 conductor plates in the line, there being a gap between each conductor plate and the ground plate, said gaps increasing in width toward the said medial line.

7. A device of the character described, 10 comprising a coil adapted to be placed in a line to be protected, a ground plate extending longitudinally of the coil for its entire length and being separated from the coil by a gap, said gap increasing in width from the 15 medial line of the ground plate in both directions toward the ends thereof, a conductor plate mounted near each end of the ground plate and extending toward the medial line thereof, means for connecting the 20 conductor plates in the line, there being a gap between each conductor plate and the ground plate, said gaps increasing in width toward the said medial line, the free ends of 25 the conductor plates being curved away from the ground plate, and means for grounding the discharge from the conductor plates.

8. A device of the character described,

comprising a coil adapted to be placed in a line to be protected, a ground plate extending longitudinally of the coil for its entire length and being separated from the coil by 30 a gap, said gap increasing in width from the medial line of the ground plate in both directions toward the ends thereof, a conductor plate mounted near each end of the ground plate and extending toward the medial line thereof, means for connecting the 35 conductor plates in the line, there being a gap between each conductor plate and the ground plate, said gaps increasing in width toward the said medial line, the free ends of 40 the conductor plates being curved away from the ground plate, and means for grounding the discharge from the conductor plates.

This specification signed and witnessed 45 this sixth day of May, 1920.
